UNITED STATES PATENT OFFICE.

SAMUEL L. ALLEN, OF CINNAMINSON, NEW JERSEY.

CULTIVATOR.

SPECIFICATION forming part of Letters Patent No. 509,857, dated December 5, 1893.

Application filed February 3, 1892. Serial No. 420,175. (No model.)

To all whom it may concern:

Be it known that I, SAMUEL L. ALLEN, a citizen of the United States, residing at Cinnaminson, in the county of Burlington and State of New Jersey, have invented certain new and useful Improvements in Cultivators, of which the following is a full specification.

My invention relates to cultivators and consists of certain improved features, therein having special reference to the manner of securing certain of the parts together, to the construction and operation of the marker to the manner of varying the depth of cut of the implement, &c., as hereinafter fully detailed.

Referring to the accompanying drawings: Figure 1 is a side elevation of a cultivator embodying my improvements. Fig. 2 is a plan view thereof with the handle levers broken away. Fig. 3 is an enlarged transverse sectional view in the plane of $\alpha\alpha$ Fig. 2. Fig. 4 is an enlarged longitudinal section through the marking iron, and Figs. 5, 6 and 7 respectively represent on an enlarged scale a plan view, a side elevation and an end elevation of the bearing box or block at the rear of the side bar.

A is the central bar and B B the two side bars of the cultivator frame.

E E are the handles connected at their front ends to the central bar and supported by the brace I and the bracket I', the bracket being bolted to the central bar and the brace to the bracket.

The side bars B B are hinged between the plates C C' near the front end of the central bar and are connected at their rear ends with the expanders F F' through the bearing blocks L, presently to be described. The inner ends of the expanders F' are pivoted to lugs on the bracket I' which supports the handle brace I.

F³ is an open handle lever pivoted at f to a sliding piece F⁵ on which is mounted the toothed piece F⁴ a handle operated stop or pawl within the open lever F³ engaging with said toothed piece F⁴ as the lever is set in any angular position.

J is a connecting piece between the lever F³ and the bracket I', while F² F³ are arms pivotally connecting the arms F' with the sliding piece F⁵ the whole construction and operation of the hinge plates, side bars, ex-

panders and handle lever being in the main similar to the corresponding parts shown and described in my United States Letters Patent No. 466,282, dated December 29, 1891.

An important variation exists however between the manner of connecting the expanders F to the side bars B in the present case, and that shown in my previous cultivator patents, No. 387,332, dated August 7, 1888; No. 424,946, dated April 8, 1890, and the above named patent, No. 466,282, dated December 29, 1891. In all three of these last mentioned patents a bearing block is bolted to the rear of each side bar and a tooth having a standard similar to G' Figs. 1 and 2 is secured near the rear of each side bar by having a staple bolt pass up through the tooth standard and through holes in the bearing block, said bolt being provided with nuts on the top of said block. In all three of the above patents moreover the outer end of the expander bar is interposed between the tooth standard and the bearing block and has one leg of the staple bolt pass through said expander, thus securing it in place. By this mode of connection it will be seen that the tooth with its standard similar to G' cannot be removed from the frame without severing the connection between the expander and the side bar since the staple bolt must be removed. In my present application I obviate this difficulty by so constructing the bearing block that the expander is connected thereto by a bolt separate from the staple bolt.

L is the bearing block secured to the side bar B by bolts l² passing through the holes l⁴ (see Figs. 5, 6 and 7) and through the bar. The block L has the usual holes l³ through which pass the legs of the staple bolt l' (Figs. 1 and 2) which staple bolt secures the standard G' of the tooth G to the block. The block L is provided with the lugs or ears L' between which the end of the expander F fits, a bolt l¹ serving to hold the expander pivoted between said ears. By this construction the staple bolt l' may be removed without disconnecting the expander.

D' is the depth regulating wheel the purpose of which is similar to that of the wheel D in my United States Letters Patent No. 463,609, dated November 24, 1891. There are important differences between the construc-

tion and operation of the wheel controlling handle lever and adjacent parts in the present case and in the said Patent No. 463,609. In the said patent the depth regulating wheel 5 is journaled in what is virtually a single open rigid lever, fulcrumed directly to the frame having the operating handle pass directly backward on the side of the fulcrum opposite the wheel. In said Patent No. 10 463,609, the convexly curved tooth-piece with which the handle operated stop or pawl within the open lever engages, is on the side of the fulcrum next the operator, being bolted directly to the central bar.

15 By my improved construction as shown in my present application I change the leverage in such a manner as to better control the operation of the depth regulating wheel. To this end the wheel D' is journaled within the 20 open curved arm D which is pivoted at its rear end at d to the central bar A, the side bar being broken away in Fig. 1 to clearly show this arrangement.

The open handle D³ is rigidly bolted at d² 25 to the arm D on the same side of the pivot or fulcrum d, as the wheel D' and the handle is further braced by being bolted at d' to the connection D² of the arm D. The convexly curved tooth-piece C² with which the handle 30 operated stop d⁴ within the bar D³ engages, is bolted to the upper hinge plate C by the same bolts c, Figs. 1 and 2, that secure the upper and lower hinge plates C C' together, and to the central bar. The tooth piece C² is thus 35 arranged on the opposite side of the fulcrum d to the operator, between said fulcrum and the wheel D'. It will be observed that the handles F³ and D³ in Fig. 2 are broken away near their lower ends so as to show more 40 clearly the parts lying beneath.

Aside from the regulating wheel D' the depth of cut of the implement teeth may be regulated by means of the side runners H, the upright portions of which are provided 45 with a series of holes h, whereby they may be bolted at varying heights to the downwardly bent portions of the bars H'. The horizontal portions of the bars H' pass each other through the clip K, (see Figs. 1, 2 and 3), beneath the side bars B B. The clip K rests on the central bar A and is provided with the bolt k which when screwed tightly down upon the top of the central bar, firmly clamps the bars H' with the runners H attached thereto 55 between the bottom of the central and side bars and the portion k' of the clip.

By varying the height of the runners H, on the bars H', the depth of cut of the implement teeth is varied when the wheel D' is not 60 used for this purpose and the position of the runners laterally may be varied at will in a manner readily apparent.

An important feature of my invention consists in the peculiar construction and operation of the marking devices.

I employ for the purpose of marking the

rows, two sets of similar appliances oppositely mounted, one for each side of the implement and so arranged that one of the marking irons may be raised while the other is in use.

R R' are two bars preferably of wood passing across the handle bars E near the bottom thereof, and having secured thereto the marking devices.

S is a metal plate which, with the staple bolts T serve to clamp the bars R R' on the handle bars. The staple bolts T embrace the bars R R' and also the handle bars E in the manner shown in Figs. 1 and 2, and when the nuts on said bolts are screwed down above the plate S, the bars R R' are firmly held in place. The rod R has near its outer end the hook n, and farther in, the screw eye r on the rear side of the bar. The bent rod N N² is mounted 85 to turn in the screw eye and hook as bearings, and has pivotally mounted on the rear end thereof the marking iron M. This marking iron is made somewhat in the shape of a flat, rectangular pan having the opening m at the front thereof and the sharp edge m' along the bottom, being so shaped that when in use it will cut into the ground and hold up with earth the proper weight, to make a clear mark. The upward and inwardly bent end N² of the 90 rod N acts as a handle to determine the position of the marking iron M.

P is a seat for the marker handle N², being bolted to the bar R, as shown and provided with the notch p in which the said handle N² 100 may rest when the marking iron is lifted off the ground.

The rod N' with its handle N³ mounted in bearings n' r' with which the bar R' is provided, and the marking iron M' as well as the seat p' are identical in construction with the similar parts N N² n r and P connected with the bar R. The drawings represent the marker M in position for use and the marker M' raised up off the ground, the handle N³ being 110 hooked into the notch p'. The marking iron from its peculiar shape is light so that it carries easily when raised up.

The bars R R' may be graduated along their rear sides so that they may readily be 115 set to overlap each other more or less as desired, making a mark at any distance to one side of the center.

I claim—

1. In an adjustable-side-bar cultivator the 120 combination of the side bar, the expander F, a detachable bearing block L secured to said bar provided with tooth-standard-retaining devices, said block being further provided with one or more ears L' and a separate fastening bolt l whereby the expander may be pivoted to said block independent of the tooth standard substantially as described.

2. In an adjustable-side-bar cultivator, the 125 combination of the expander F, side bar B, and block L, having the tooth-standard-secur- 130 ing staple bolt l' seated therein, said block

being further provided with ears L', having the expander-pivoting bolt l substantially as described.

3. In a cultivator a depth regulating device consisting of a curved arm D pivoted at its rear end d to the central bar A, having journaled within it the wheel D', and a rearwardly projecting open handle D³, rigidly bolted at d² to the arm D on the same side of the pivot d as the wheel D', and also bolted at d' to the connection D² of the arm D, substantially as described.

4. In a cultivator a depth regulating device consisting of a curved arm D, fulcrumed at d to the central bar, a wheel D' journaled within said arm, a rearwardly projecting open handle bar D³ rigidly connected to said curved arm forward of the fulcrum between said fulcrum and said wheel, a handle operated stop or pawl d⁴ within said handle bar, and a curved tooth piece C² between said fulcrum and wheel with which said stop or pawl engages, substantially as and for the purposes described.

25 5. In a cultivator the side bar B connected at its rear end with expanders F F' through the bearing block L secured to the side bar by bolts l² passing through the holes l⁴, and through the bar and provided with ears L', and a bolt l, all arranged and operated, substantially as and for the purposes described.

6. In a cultivator a pair of adjustable side runners H having upright pieces in combination with separate horizontal clamping bars 30 H', having their outer ends bent downward

and means for securing said runners at varying heights to said clamping bars, substantially as and for the purposes described.

7. A cultivator provided with a marker consisting of a bar, a rod connected to said bar, 40 and a marking iron pivoted to said rod consisting of a pan open at the front but having earth retaining sides substantially as described.

8. In a cultivator a marker bar horizontally 45 secured thereto in combination with a rod having bearings on said bar and provided with an upwardly bent handle, a marking iron connected to said rod, and a seat on said bar adapted to engage with said handle, 50 whereby the marking iron may rest on the ground or be lifted up and carried in the air, substantially as described.

9. In a cultivator the combination with the horizontally supported bar R, of the bent rod 55 N N² having bearings on said bar, the marking iron M pivoted to said rod and the seat P, bolted to said bar and provided with the notch p, substantially as described.

10. In a cultivator a marking iron consisting of a flat earth holding pan open at the front end and provided with a cutting edge substantially as described.

In witness whereof I have hereunto set my hand.

SAMUEL L. ALLEN.
